UNITED STATES PATENT OFFICE.

JAMES C. CAMPBELL, OF NEW YORK, N. Y.

VACUUM PNEUMATIC HAMMER.

1,342,984.

Specification of Letters Patent.

Patented June 8, 1920.

Application filed July 15, 1916. Serial No. 109,455

To all whom it may concern:

Be it known that I, JAMES C. CAMPBELL, a citizen of the United States, residing at New York, in the county of New York and State of New York, have invented certain new and useful Improvements in Vacuum Pneumatic Hammers, of which the following is a specification.

This invention relates to vacuo-pneumatic power hammers and its novelty consists in the construction and adaptation of the parts as will be more fully hereinafter pointed out.

The purpose of the invention is to produce a power hammer of simple construction, not likely to get out of order and of rapid and efficient operation.

In the drawings there is illustrated a preferred form of hammer embodying my invention. Figure 1 is a central longitudinal section of the device with the parts shown in the positions they assume when at rest; Fig. 2 is a section on the plane of the line 2-2 in Fig. 1 showing the piston hammer retracted; Fig. 3 is a section similar to Fig. 2 showing the piston hammer in a forward position and with some of the parts in elevation; Fig. 4 is a section on the plane of the line 4-4 in Fig. 3, showing the piston hammer retracted; Fig. 5 is a transverse section on the plane of the line 5-5 in Fig. 4; Fig. 6 is a view similar to Fig. 1, showing the piston hammer in an intermediate position; and Fig. 7 is a miniature view of the entire device. Fig. 8 is a detail sectional view on the line 8-8 of Fig. 4. Fig. 9 is a detail sectional view on the line 9-9 of Fig. 1.

In the drawings, 10 is a casing preferably of cylindrical form, and secured to it in any suitable manner is a second casing indicated at 11. The casing 10 is slightly restricted at 12 to form a shoulder against which there is adapted to rest an enlarged annulus 13 of a sleeve 14 which is secured firmly within the casing 10 and is generally cylindrical in form but is longitudinally truncated at several places as indicated at 15 (see Fig. 5) whereby there are clearances between the inner surface of the casing and the outer surface of the sleeve forming air passageways. There are a series of ports, indicated at 16, 17 and 18, arranged at intervals along the sleeve and they gradually increase in width from the rear toward the front of the tool. Slidably arranged within the casing 10 and sleeve 14 is a cylinder, 20, considerably

longer than the sleeve, to the forward end of which by threads 21 or in any other suitable manner is secured a tool holder 22 and which is provided with a central bore adapted to receive the shank of a tool indicated at 23. The cylinder is provided at intervals with a series of ports, indicated at 26, 27 and 28, all of the same size, and circularly arranged and adapted to register with the ports 16, 17 and 18 of the sleeve 14. Tightly fitting within the cylinder 20 there is arranged to reciprocate piston hammer 30. A coiled spring 31 is inserted within the casing 10 between the holder 22 and sleeve 14. The casing 10 is provided with a guide finger 32 with which the tool holder 22 is in slidable contact.

The second casing 11 constitutes part of a compressor and is of rounded form and contains the air controlling or compressing device in the form of an eccentrically set revolving roll 35 mounted to rotate in suitable bearings formed in the casing and actuated from a source of power not shown. It is provided with a cam groove 36 and with a transverse vane 37 which slides radially with respect to its center and is provided with suitable packing at each edge and contacts with the interior of the casing. By the rotation of this vane the air within the casing is alternately compressed and allowed to expand and the device forms in effect a rotary air pump although it both compresses and exhausts the air. At the side of the casing 11, there are provided ports indicated at 40 and 41, which communicate with a space 42 immediately back of the sleeve 14, which in turn communicates with the spaces 15, 15, the port 40 being an inlet port and the port 41 an outlet port when the vane 37 rotates clockwise.

A slide valve indicated at 43 is arranged in the forward end of the casing 11, and is adapted to be reciprocated laterally therein by means of a fin 44 secured thereto and which engages the cam groove 36 in the roll 35. By such reciprocation this valve alternately closes and opens the inlet port 40 and outlet port 41. The slide valve controls communication between the ports 40 and 41 respectively and other ports 40* and 41* which communicate with the interior of the piston casing 11.

A suitable handle indicated at 45 and attached to the casing 11 enables the operator to hold the tool against the work. When

the parts of the tool are at rest, they are in the position shown in Fig. 1, and even although the roll 35 and vane 37 be revolving within the casing and the slide valve 43 be actuated and the air within the casing 11 be alternately compressed and exhausted and driven through the inlet port 40 into the passageways 15 within the casing 10, and exhausted from such passageways, nevertheless there would be no movement of the piston hammer 30 because the ports of the sleeve 14 would not register with the ports of the cylinder 20 and no air would be admitted to or could escape from such cylinder.

If, however, the operator, pressing upon the handle 45, presses the tool 23 against the work and by so doing, moves the tool holder with respect to the casing 10 into the position shown in Fig. 2, thus compressing the spring 31, he will have caused the ports 16, 17 and 18 of the sleeve 14 to register with the ports 26, 27 and 28 of the cylinder 20. By this action, the air in compressed form is admitted to such ports and exhausts through such ports as the vane rotates. This variation of the density of the air in the space behind the piston hammer 30 causes the latter to vibrate or to be reciprocated rapidly within the cylinder and to strike repeated blows against the tool shank and consequently upon the tool.

When the tool holder is pressed back so that its rear end contacts with the front end of the casing 11, then, as all of the ports in the sleeve 14 register with all of the ports in the cylinder 20, there is the fullest stroke given to the piston hammer. If, however, the tool holder is only partly pressed back toward the casing 10 as illustrated in Fig. 6, the ports of the sleeve 14 will only register with a part of the ports in the cylinder 20, and will thus permit a smaller quantity of air to be delivered to and exhausted from the interior of the cylinder, thus imparting an impulse of less energy to the piston hammer. It should be noted that the space within the cylinder 20 is practically air-tight, and that the actuation of the vane 37 has the effect practically of merely rapidly varying the density of the air within this cylinder. For this reason, the cylinder is not likely to become hot and the device can be operated with comfort and without the provision of means for cooling it.

I claim:

1. In a device of the character described, the combination with a cylinder member and a piston therein, of means for operating the latter, comprising a compressor having a rotary piston, passageways for delivering fluid between the compressor and cylinder member, an automatic controlling valve for the passageways, and a mechanical connection between the controlling valve and the

rotary piston of the compressor to actuate said valve.

2. In a device of the character described, the combination with a cylinder member and a piston therein, of means for operating the latter, comprising compressing and exhausting mechanism including a cylinder and a rotary piston in the cylinder having a cam element, passageways between the compressor and cylinder member, and a reciprocatory valve controlling the passageways and operated by the cam element.

3. In a device of the character set forth, the combination with a cylinder member and a piston therein, of means for operating the latter, comprising a compressor having a rotary piston, a cam rotating with the piston, a fluid delivery passageway between the compressor and cylinder member, a suction passageway between the compressor and cylinder member, an automatic valve controlling the passageways, and means engaged and operated by the cam for actuating the valve.

4. In a device of the character set forth, the combination with a casing, of a cylinder located therein, a piston operating in the cylinder, a sleeve interposed between the cylinder and casing and having a portion spaced from the latter and provided with ports, said cylinder having ports that register with the ports of said portion of the sleeve, and means for supplying motive fluid to the space between the cylinder and sleeve.

5. In a device of the character set forth, the combination with a casing, of a cylinder slidably located therein, a piston operating in the cylinder, a sleeve interposed between the cylinder and casing and having a portion spaced from the latter and provided with ports, said cylinder having ports that move into and out of register with the ports of said portion of the sleeve on the sliding movement of the cylinder, and a spring interposed between the sleeve and cylinder for resisting the movement of the latter in one direction.

6. In a device of the character described, the combination with a casing, of an internal cylinder slidably in the casing and having ports, a sleeve interposed between the casing and internal cylinder and having a portion spaced from the casing and provided with ports with which the ports of the internal cylinder move into and out of register, a piston operating in the internal cylinder, and means for effecting the movement of said internal cylinder.

7. In a device of the character described, the combination with an outer casing, of a tool holder slidable thereon and having an internal cylinder located within the casing and slidably therein, said cylinder having lateral ports, and a sleeve interposed between

- the casing and internal cylinder and having a portion spaced from the former and provided with ports with which the ports of the cylinder move into and out of register.
- 5 8. In a device of the character described, the combination with a casing, of an internal cylinder slideable in the casing and having sets of ports, a sleeve interposed between the casing and internal cylinder and having ports with which the sets of ports of said internal cylinder successively move into and out of register upon the sliding movement of the piston, a piston operating in the internal cylinder, and means for effecting 10 the movement of the internal cylinder longitudinally of the casing.
- 15 9. In a device of the character described, the combination with an outer casing, of a tool holder slidably mounted on one end of the same, an internal cylinder fixed to the 20 tool holder and slidably mounted within the casing, said cylinder having sets of laterally disposed ports, a sleeve interposed between the casing and cylinder and having ports with which the ports of the cylinder successively align upon the sliding movements of the latter, a piston operating in the internal cylinder, and a spring interposed between the sleeve and the tool holder. 25
- In testimony whereof I affix my signature. 30

JAMES C. CAMPBELL.
